CLAIM

The ornamental design for a leg assembly for portable power source, as shown and described.

DESCRIPTION

FIG. 1 is a top-front perspective view of a preferred embodiment of a leg assembly for portable power source, the leg assembly shown in an extended configuration.

FIG. 2 is a bottom-front perspective view of the leg assembly for portable power source in FIG. 1.

FIG. 3 is a top-rear perspective view of the leg assembly for portable power source in FIG. 1.

FIG. 4 is a bottom-rear perspective view of the leg assembly for portable power source in FIG. 1.

FIG. 5 is a top-front perspective view of the leg assembly for portable power source in FIG. 1, the leg assembly shown in a folded configuration;

FIG. 6 is a bottom-front perspective view of the leg assembly for portable power source in FIG. 5.

FIG. 7 is a top-rear perspective view of the leg assembly for portable power source in FIG. 5.

FIG. 8 is a bottom-rear perspective view of the leg assembly for portable power source in FIG. 5.

FIG. 9 is a top-front perspective view of the leg assembly for portable power source shown in FIG. 1, the leg assembly attached to a portable light power source with telescoping light attachment shown in broken lines.

FIG. 10 is a top-front perspective view of the leg assembly for portable power source shown in FIG. 5, the leg assembly attached to a portable light power source with telescoping light attachment shown in broken lines.

FIG. 11 is a top-rear perspective view of the leg assembly for portable power source shown in FIG. 1, the leg assembly attached to a portable light power source with telescoping light attachment shown in broken lines; and,

FIG. 12 is a top-rear perspective view of the leg assembly for portable power source shown in FIG. 5, the leg assembly attached to a portable light power source with telescoping light attachment shown in broken lines.

The broken lines showing the portable light power source with telescoping light attachment, or portions thereof, in FIGS. 9-12 are for illustrative or environmental purposes only and do not form any part of the claimed design.
